CLAIM

The ornamental design for a smoke detector with remote alarm silencing means, as shown and described.

DESCRIPTION

FIG. 1 is a front, top and side perspective view of the smoke detector with remote alarm silencing means showing our new design;

FIG. 2 is a bottom plan view thereof;

FIG. 3 is a front elevational view thereof, the rear elevational view and the side elevational views being the same as this front elevational view; and,

FIG. 4 is a top plan view thereof.
